UNITED STATES PATENT OFFICE.

ALONZO C. CAMPBELL, OF ASHEVILLE, NORTH CAROLINA.

COAL-WASHER AND ORE-CONCENTRATOR.

1,113,876.

Specification of Letters Patent. Patented Oct. 13, 1914.

Application filed May 3, 1913. Serial No. 765,977.

To all whom it may concern:

Be it known that I, ALONZO C. CAMPBELL, a citizen of the United States, and a resident of Asheville, in the county of Buncombe and State of North Carolina, have invented a new and Improved Coal-Washer and Ore-Concentrator; of which the following is a full, clear, and exact description.

The invention relates to coal washers and ore concentrators, such as shown and described in the Letters Patent of the United States, No. 695,790, No. 835,397, and No. 898,314, granted to me on March 18, 1902, November 6, 1906, and September 8, 1908, respectively, and in the application for Letters Patent of the United States, No. 701,788, filed by me on June 5, 1912.

The object of the present invention is to provide certain new and useful improvements in coal washers and ore concentrators of the type mentioned, whereby a novel percussive action is given to the pan to facilitate the separation of the heavier and lighter materials, and to allow convenient adjustment of the parts to suit the nature of the materials under treatment.

In order to produce the desired result use is made of a pan mounted to oscillate, a revoluble wheel provided on its peripheral face with a percussion lug adapted to engage one end of the said pan, and a spring device connected with the said pan to draw the latter toward the said wheel and to exert an upward and forward pull on the pan. Use is also made of a pan provided with perforate, transverse riffles, pivoted at their lower ends on transverse rods held in the sides of the pan, the free end of a riffle extending approximately half way under the next riffle ahead.

A practical embodiment of the invention is represented in the accompanying drawings forming a part of this specification, in which similar characters of reference indicate corresponding parts in all the views.

Figure 1 is a plan view of the coal washer and ore concentrator; Fig. 2 is a longitudinal section of the same; Fig. 3 is a cross section of the same; Fig. 4 is a reduced rear end elevation of the same, the ceiling of the housing being shown in section; Fig. 5 is a side elevation of the coal washer and ore concentrator provided with two co-operative pans receiving a percussive action from one revoluble wheel, the floor and ceiling of the housing being shown in section; Fig. 6 is a

side elevation of a modified form of the spring device, the overhead supporting beams being shown in section; and Fig. 7 is a detail side view partly in section, of the means for supporting the riffles.

The bottom A' of the pan A is connected by hinges B, B' with legs B², B³ connected at their lower ends by hinges B⁴, B⁵ with blocks C, C' bolted or otherwise secured to a support D of any approved construction. The leg B² is arranged at the forward end of the pan A while the leg B³ is arranged near the rear or tail end, and the leg B² is somewhat longer than the leg B³.

On the block C are mounted bearings E in which is mounted to turn a shaft F provided with a pulley F' connected by belt with other machinery for imparting a rotary motion to the shaft F. On the shaft F is secured a wheel G provided on its peripheral face with a percussion lug G' adapted to engage a bumping block H secured on the forward end of the keel I forming part of the pan A. In order to hold the bumping block H in contact with the peripheral face of the wheel G and its percussion lug G' the following arrangement is made: On the bumping block H is secured an eye J connected by a wire, rope or other suitable flexible connection J' with an eye J² forming part of a spring device K, which may be either in the form shown in Fig. 4 or in the form shown in Fig. 6. The spring device K shown in Fig. 4 consists of a spring board K' to the free end of which is secured the eye J², and the said spring board K' is fastened by a bolt K³ to a timber K³ attached to the under side of an overhead support K⁴, such as a ceiling or the like. The spring board K' is engaged by an adjusting screw K⁵ for regulating the tension of the spring board K'.

In the modified form shown in Fig. 6 the eye J² is mounted to slide in a bearing K⁶ held on a board K⁷ attached to the overhead support K⁴, and the upper end of the eye J² is pressed on by a spring K⁸ so as to yieldingly support the eye J². By adjusting the nut K⁹ at the top end of the eye J² the tension of the spring K⁸ can be regulated.

By reference to Figs. 2 and 5, it will be noticed that the flexible connection J' extends upwardly and slightly forwardly relative to the pan A so that the bumping block H is held in contact with the peripheral face of the wheel G and its percussion lug G'.

The tail end of the pan A is provided with an eye L connected with the lower end of a retention device in the form of a wire rope L' connected at its upper end to an eye L² 5 spring-supported on a board L³ secured to the overhead support K⁴ previously mentioned.

The detail construction of the pan A is as follows: From the bottom A' rise the 10 sides A², the head piece A³ and the tail piece A⁴, and a short distance from the head piece A³ is arranged a transversely extending barrier N to form with the head piece A³ a concentrate pocket N'. The pocket N' is provided at the bottom with openings N² for the discharge of the concentrates, as hereinafter more fully explained. The lower edge of the barrier block N is provided with openings N³ opening into the 20 pocket N' for the passage of concentrates from the screen pocket O' arranged at the head end of the pan A. This screen pocket O' is formed by a screen O extending from the barrier block N to the bottom A' a distance from the barrier block N, as plainly indicated in Fig. 2. The bottom A' of the pan A is slightly inclined from the tail end of the machine toward the head, and the front portion A⁵ of the bottom A' has 25 a steeper inclination than the remaining portion of the bottom as will be readily understood by reference to Fig. 2, the said front portion A⁵ forming the bottom of the pocket O'.

30 Within the pan A are arranged series of transversely extending perforate riffles P mounted to swing on rods P' held between pairs of superimposed bars A⁶, A⁷ (see Fig. 3) attached to the bottom A' and 35 the sides A² of the pan A. By reference to Fig. 2 it will be noticed that the riffles extend from the rods P' in a forward direction and their free ends rest on the bottom A' except the foremost riffles which have 40 their free ends resting on the top of the screen O. It will also be noticed that each riffle P extends with its forward end under the next following riffle ahead a distance approximately of half the length of this 45 riffle. By reference to Fig. 1 it will be noticed that the riffles on each rod P' are slightly spaced apart by the use of suitable washers so as to facilitate the passage of the water onto the riffles, as hereinafter 50 more fully explained.

55 As shown in Fig. 5, two pans A are arranged on opposite sides of the wheel G, and two percussion lugs G' are arranged on the peripheral face of the wheel G diametrically opposite each other. The two flexible connections J' of the two pans A connect with the eye J² of the spring board K', the eye J² being located directly above the center of the wheel G.

60 65 The operation is as follows: When the

shaft F is rotated then the centrifugal inertia of the wheel G together with the percussion lug G' affords the necessary impact on the bumping block H to lurch the pan A to the right with such force and amplitude as is in keeping, first, with the weight of the loaded pan A, second, with the tension of the spring device K, and, third, with the radial inclination of the legs B², B³. When the legs B², B³ stand erect most of 70 the weight of the loaded pan is borne by them, particularly the hind legs B³. Much of the weight is held by the spring device K. When the pan A recoils from the impact given to it, as above described, it is by 75 restraint held to the combined radial movement of the hinged legs B², B³. When the pan is describing this path, the spring device is increasing in tension or lifting effect while the inclining legs are diminishing 80 their sustaining effect. The tension of the spring device is gaged in general to withstand the burden of weight and inertia that is brought to bear upon it throughout so that it may permit of any desired amplitude of the pan A under any given structural conditions and any given periodicity 85 of reciprocation; thus, for instance, if the wheel G should have a speed say of 120 revolutions per minute the pan A should 90 recoil say about six inches and return in time to just meet the percussion lug G' at the next revolution of the wheel G, so that the total impact is the sum of the arrested motion of the pan A and the centrifugal 95 impact of the percussion lug G'. The tension of the spring device K may be connected so that the impact shall be every other revolution of the percussion lug G', so that the pan A receives sixty bumps per 100 minute instead of 120. From the foregoing 105 it will be noticed that any desired effect may be reached by the adjustment of one or more of the constructive parts; that is, the legs B², B³ as to their length and inclination; 110 total weight of the pan and load; the inclination of the flexible connection J'; the weight and speed of the wheel G; thickness of the percussion lug G'; etc., all of which should be in keeping with the needs of the 115 case whether the apparatus is used for coal washing, coarse or fine; or for washing ore having baser metals or precious metals.

The reciprocating movement of the pan A due to the joint action of the spring device 120 K and its flexible connection J' with the pan A and the legs B², B³ is very peculiar and very effective, as will presently appear. The spring device in the present case is designed to act in conjunction with the legs 125 B², B³, the same as a toggle joint movement intervening between the power and the work, and is to hold the total weight, first, against the variable component of gravity, and, second, as against inertia of impact. 130

At the instant following the impact, the pan A has its maximum velocity which is then retarded by the pull of the spring device K, but the normal effective force of the spring device is counteracted in a great degree by the increasing component of gravity of the load to that extent at times that the pan A settles back on its inclining legs B³, B⁴, not being able to rise at all even though the spring device be at its maximum tension at the time. In this event the tension of the spring device is increased so that the periodicity and amplitude shall be correct for the given purpose. In the ordinary spring device now generally used the action and reaction are equal and opposed; that is to say, the recoil of the spring has the same violence as the impact of the percussion lug. This violent return jerk has a tendency to unseat the bed and all would flow toward the tail of the pan and there would be only a shaking table like that of a screen; furthermore, there would be only a shuffling to and fro but no carrying effect toward the head would be produced. In the present coöperating mechanical movement the pan A nearing the terminus of the stroke backward is exceedingly slow both going and coming, and there is a well-gaged accelerated movement as the knuckle of the toggle joint straightens up and the spring device has its full unrestrained effect.

It will be understood that the force of the impact is not spent upon the wheel G as if the latter were at a standstill, but it is the centrifugal inertia of the wheel that takes the impact, and that force increases with the square of the velocity. Again, with the double action pans A, A shown in Fig. 5, the impacts are at the same instant and are counteractive. That they may be constrained to bump at the same instant, the one spring device and the one connection operate both pans A, A, all other conditions being symmetrical.

The hind legs B³ are made a little shorter than the front legs B², as previously mentioned, so that the tail end of the pan A is somewhat lower at the terminus of the back stroke. This is done for the purpose that the flow may at that instant be more precipitate to favor the tailings discharge. Then again, at the instant of impact, the pan A is practically level, thus favoring the discharge of the headings at the opportune time. There is another new and advantageous feature as an outcome of the curvilinear path of the pan A. By noting the dotted curve indicating the path of the legs, it will be noted that it is downward toward the rear or tail while it is downward toward the head. It will be understood that during the backward throw of the pan A there is a tendency or a sort of dropping from under the bed, and since the water on the surface

together with its burden of lighter stuff is under least restraint, it will flow more precipitately to the tail discharge, while the more dense stuff is intermeshed with the riffles P and more or less compacted, and will undergo such buoyancy as should serve to give further enrichment. On the other hand when the pan A is moving forward the reverse action takes effect, that is to say, the bed grows weightier and the compacted dense material clings persistently to the riffles and partakes of the forward throw due to the percussive action. In using the machine for washing coal, for instance, the coal and water are conveyed onto the pan A at about one-third the distance from the head thereof.

The percussive action described together with the multivariable curvilinear movements and the multi-closely interlapping riffles P serve to cause a separation of the dense material from the less dense material, the dense material being again separated into fine stuff and coarse stuff. The fine stuff becomes compacted in degree and intermeshes with the closely interlapping riffles. The coarse dense stuff is jigged and re-jigged on the surface of the massed riffles P as it traverses the pan A toward the head. The coarse dense stuff masses at the head barrier N, finally clambers over the same and into the pocket N' from which it passes through the openings N² into a receptacle Q mounted on the support D. The receptacle Q is provided in its bottom with an opening D' leading to a sluice Q' for carrying off the dense material to a suitable place of discharge. The rods P' together with the beading of the riffles around the rods serve as most efficient riffles to check the back flow of the concentrate. The fine dense stuff thoroughly enriched by the time it approaches the head of the pan A is impelled to pass through the fixed screen O into the hutch pocket O', from which it passes into the openings N³ and into the pocket N' to be discharged with the coarse dense stuff, as previously mentioned. All the lighter stuff, such as coal, that cannot traverse the closely interlayered riffles or cannot stem the back flow of the water as an only resort discharges at the tail of the pan A into a box R from which it passes to a sluiceway to be carried to a suitable place of discharge.

It will be noticed that by the construction of the riffles described they are thoroughly intermeshed with the bed of the material. The greatest trouble heretofore has been the rigid compacting of the fine stuff under the riffles thus destroying the jigging and panning efficiency and reducing the capacity. In some constructions there is excessive compacting while in others there is undue flow and diffusion and one aggravates the other. There was either insufficient action or

cessive action. The multiple riffles in cross section if thoroughly fitting throughout the interstitial spacings of the riffles enable much closer interlapping and protection against watery diffusion. This mat of meshing has also a retentive power as against backsiding and accelerates the travel of the concentrates to the head.

The multiple riffles have lateral openings, as previously mentioned, so as to provide longitudinal cuts throughout the bed and which cuts give the needed diffusive power to the surface water. The superimposed bars A^6 and A^7 are provided with a large number of recesses for the reception of the ends of the rods P' so as to allow adjusting the rods with a view to move the free ends of a riffle a greater or less distance under the next riffle ahead. It will be noticed that the riffles on account of being adjustable can be readily adapted to the needs of any particular case, and the riffles also serve as lodgments for the coarser material in the longitudinal channels; that is, stuff that is too large passes under the closely-lapping riffles. The retention connection L' at the tail end of the pan A serves the double purpose, first, to cut short the amplitude of the pan in its backward and downward terminal movement; and, second, to give a downward lurch or impetus to the bed and also to the riffles.

It will be understood that at the instant of the impact of the percussion lug the path of the movement is horizontal, or nearly so, the path at all times being tangent to the curve described by the hinged legs B^2 , B^3 , as indicated by the dotted lines; that is to say, the path is a true circle, the legs B^2 , B^3 being radii to the circle.

The effect of the downward lurch is to settle the bed, and to close down the riffles snug to the bottom, or to settle the dense stuff and to disengage the lighter stuff at the instant of copious tail discharge. The backward impulse of the percussion lug serves to cause a violent rush of the entire bed toward the head thus giving buoyancy to their riffles and a flow of the diffused mass either under the riffles or through the perforations upwardly, carrying the lighter material to the surface flow. It is at this juncture that the arresting cord serves to settle the diffused bed downwardly.

Having thus described my invention, I claim as new and desire to secure by Letters Patent:

1. A machine of the class described provided with a pan, means for oscillating the pan and imparting percussive action to the same, transversely-extending swinging riffles within the said pan and inclined forwardly and downwardly, the riffles being fulcrumed at their elevated ends and the

forward end of one riffle extending approximately half way under the next riffle ahead. 65

2. A machine of the class described provided with a pan, legs for supporting the pan and mounted to swing, one of the legs being at the head of the pan and being longer than the other leg at the rear end of the pan, means for oscillating the pan and imparting percussive action to the same, and transversely-extending swinging riffles within the said pan and inclined forwardly and downwardly, the riffles being fulcrumed at their elevated ends, and the forward end of one riffle extending approximately half way under the next riffle ahead. 70 75

3. A machine of the class described, provided with a pan, provided at its head with a transverse barrier forming with the head end of the pan a concentrate pocket provided in its bottom with discharge openings, means for oscillating the pan and imparting percussive action to the same, transversely-extending swinging riffles within the said pan and inclined forwardly and downwardly, the riffles being fulcrumed at their elevated ends and the forward end of one riffle extending approximately half way under the next riffle ahead. 80 85

4. A machine of the class described, provided with a pan, provided at its head with a transverse barrier spaced from the head end to form with the same a concentrate pocket, the barrier having openings leading to the said pocket and the latter having discharge openings in its bottom, a screen in the head end of the pan and terminating at 100 the said barrier above the openings therein, means for oscillating the pan and imparting percussive action to the same, and transversely-extending swinging riffles within the said pan and inclined forwardly and downwardly, the riffles being fulcrumed at their elevated ends and the forward end of one riffle extending approximately half way under the next riffle ahead. 105

5. A machine of the class described provided with a pan provided with riffles, swing legs pivotally connected with the pan to allow the pan to oscillate, the legs being of unequal length and the shorter one being at the tail end of the pan, a revolute wheel 110 provided at its peripheral face with a percussion lug adapted to engage the head of the said pan, the legs of the pan being approximately vertical at the inception of the percussive stroke, a flexible connection attached at one end to the head of the pan and extending upwardly and forwardly, and a spring device connected with the other end of the said flexible connection. 115

6. A machine of the class described provided with a pan provided with riffles, swing legs pivotally connected with the pan to allow the pan to oscillate, the legs being of 120 125

- unequal length and the shorter one being at the tail end of the pan, a revolute wheel provided at its peripheral face with a percussion lug adapted to engage the head of the said pan, the legs of the pan being approximately vertical at the inception of the percussive stroke, a flexible connection attached at one end to the head of the pan and extending upwardly and forwardly therefrom, and an adjustable spring device connected with the other end of the said wire rope.
7. A machine of the class described provided with a pan provided with ruffles, swing legs pivotally connected with the pan to allow the pan to oscillate, the legs being of different lengths and the shorter one being at the tail end of the pan, a revolute wheel provided at its peripheral face with a percussion lug adapted to engage the head of the said pan, the legs of the pan being approximately vertical at the inception of the percussive stroke, a flexible connection attached at one end to the head of the pan and extending upwardly and forwardly, a spring device connected with the other end of the said flexible connection, and a flexible retaining connection connected with the tail end of the pan.
8. A machine of the class described, comprising a revolute wheel provided with percussion lugs, pans on opposite sides of the said wheel and having bumper heads adapted to engage the peripheral face of the said wheel and the said percussion lug, swing legs for the said pans, an overhead spring device and a flexible connection secured to the spring device and to the head end of each of the said pans to draw the pans to the wheel and to assist in sustaining the load.
9. A machine of the class described, comprising a revolute wheel provided with percussion lugs, pans on opposite sides of the said wheel and having bumper heads adapted to engage the peripheral face of the said wheel and the said percussion lug, swing legs for the said pans, an overhead spring device, a flexible connection secured to the spring device and to the head end of each of the said pans to draw the pans to the wheel and assist in sustaining the load, and spring retention means connected with the tail ends of the said pans.
10. In a machine of the class described, a pan, means for oscillating the pan and imparting percussive action to the same, and transversely extending ruffles pivoted to swing freely, said ruffles being inclined and overlapping one another.
11. In a machine of the class described, a pan provided with ruffles, means for mounting the pan to permit it to move longitudinally and downwardly, a percussive impelling device acting on the pan, and a spring device connected with the head of the pan to retract the movements thereof with decreased force toward the impelling device.
12. In a machine of the class described, a pan provided with ruffles, swinging legs of unequal length pivotally connected with the pan, the longer leg being at the forward end of the pan, whereby the pan is permitted to move longitudinally and downwardly, means for imparting a percussive action to the pan, and an over head spring device connected with the head of the pan and retracting the movements thereof with decreased force toward the percussive means.
13. In a machine of the class described, a pan provided with ruffles, swinging legs of unequal length pivotally connected with the pan, the longer legs being at the forward end of said pan, whereby the pan is permitted to move longitudinally and downwardly, a percussive impelling device acting on the pan, and an overhead spring device flexibly connected with the head end of the pan, and serving to retract the movement of the pan with decreasing force toward the impelling device.
14. In an impact-jig-pan of the class described, a pan, swinging legs pivoted to the pan, the legs being of unequal length with the shorter leg at the tail end of the pan, impact means for operating the pan, an inclined tension restraint engaging the impact head of the pan and opposing conjointly the coacting and varying components of inertia and gravity, and a vertical tension restraint engaging the tail of the pan and coacting with the short radial hindmost leg to arrest the precipitate downthrow of the tail, and to react in the initial centripetal uplift.
15. In an impact-jig-pan of the class described two pans, swinging legs pivoted to each pan, the shorter legs being at the tail end of the pan, a single tensional force engaging a vertical connecting rod with bearings to maintain a fixed line of movement, a terminal eye on the connecting rod linking with two inclined members secured to the opposing heads of the pans, and impact means for simultaneously giving impetus to the two pans in a quarterly arc rearward and downward, the recoil of the spring restoring the two pans simultaneously to the impact means, the reciprocation of the two pans being by constraint the same in speed and amplitude.
- In testimony whereof I have signed my name to this specification in the presence of two subscribing witnesses.
